US00D691980S

(12) **United States Design Patent**
Park

(10) **Patent No.:** **US D691,980 S**
(45) **Date of Patent:** **** Oct. 22, 2013**

(54) **MOBILE TERMINAL**

(75) Inventor: **Jun-Sang Park**, Anyang-si (KR)

(73) Assignee: **Samsung Electronics Co., Ltd.**,
Suwon-si (KR)

(**) Term: **14 Years**

(21) Appl. No.: **29/416,651**

(22) Filed: **Mar. 26, 2012**

(30) **Foreign Application Priority Data**

Oct. 14, 2011 (KR) 30-2011-0042809

(51) **LOC (9) Cl.** **14-03**

(52) **U.S. Cl.**

USPC ..... **D14/138 G**; D14/341

(58) **Field of Classification Search**

USPC ..... D14/138 G, 138 AD, 341, 346, 138 R,
D14/138 AC, 496, 203.1, 203.4, 203.7, 248,

(57) **CLAIM**

The ornamental design for a mobile terminal, as shown and described.

DESCRIPTION

FIG. 1 is a perspective view of a mobile terminal;
FIG. 2 is a front view of the mobile terminal of FIG. 1;
FIG. 3 is a rear view of the mobile terminal of FIG. 1;
FIG. 4 is a left-side view of the mobile terminal of FIG. 1;
FIG. 5 is a right-side view of the mobile terminal of FIG. 1;
FIG. 6 is a top plan view of the mobile terminal of FIG. 1;
FIG. 7 is a bottom plan view of the mobile terminal of FIG. 1;
FIG. 8 is a perspective view of the rear of the mobile terminal of FIG. 1; and,
FIG. 9 is a perspective view of the rear of the mobile terminal of FIG. 1 in which an upright position of a cover of the mobile phone is illustrated to further show an ornamental aspect of my claimed design.

1 Claim, 7 Drawing Sheets
